CLAIM

The ornamental design for a toy car, as shown and described.

DESCRIPTION

FIG. 1 is a front, left and top perspective view of a first embodiment of a toy car, showing my new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a front, left and top perspective view of the toy car, shown in an environment of use.

FIG. 9 is a front, left and top perspective view of a second embodiment of a toy car, showing my new design.

FIG. 10 is a front view thereof.

FIG. 11 is a rear view thereof.

FIG. 12 is a right side view thereof.

FIG. 13 is a left side view thereof.

FIG. 14 is a top view thereof.

FIG. 15 is a bottom view thereof; and,

FIG. 16 is a front, left and top perspective view of the toy car, shown in an environment of use.

The broken lines showing the toy car are included to illustrate portions of the article and do not form part of the claimed design. The additional broken lines shown in FIGS. 8 and 16 are for illustrating environmental subject matter only and do not form part thereof.

1 Claim, 16 Drawing Sheets
